UNITED STATES PATENT OFFICE.

JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

RANGE.

1,416,478.

Specification of Letters Patent. Patented May 16, 1922.

Application filed September 10, 1919. Serial No. 322,797.

To all whom it may concern:

Be it known that I, JOSEPH F. LAMB, a citizen of the United States, and a resident of New Britain, county of Hartford, State of Connecticut, have invented certain new and useful Improvements in a Range, of which the following is a specification.

This invention has as its object to provide an improved electric range having features 10 of novelty and advantage.

In the accompanying drawings:

Fig. 1 is a perspective view of a double sided range.

Fig. 2 is a perspective view of a single 15 sided range.

Fig. 3 is a top plan view of the range shown in Fig. 2 with the door of the oven in full open position.

Fig. 4 is a front elevational view of the 20 oven with the door partly open.

Fig. 5 is a sectional view through that portion of the stove in which the broiler is located.

Fig. 6 is a perspective view of the broiler 25 drawer with the broiler mounted therein, parts of the drawer being broken away for purpose of clearness.

Fig. 7 is a top plan view of a broiler drawer within which is positioned a pan.

Fig. 8 is a longitudinal section through 30 the drawer and pan illustrated in Fig. 7.

Referring to the drawings in detail, *a* designates the body of the range mounted on legs 10 and having a top 11, and an apron 35 12; *b*, a back upright arising from the back of the stove, and *c*, an oven carried by the back upright and extending over and spaced above the top 11.

The parts of the range are preferably 40 formed of sheet metal pressed into the proper shape. In the top 11 are the hot plates 13 and while the arrangement of these hot plates may be varied, in the double sided range shown in Fig. 1 and wherein the oven 45 is centrally located with respect to the top of the stove, two hot plates are located at each side of the oven and one hot plate is located beneath the front end of the oven. In the single sided range shown in Fig. 2 50 and wherein the oven overhangs one side of the top of the stove, there are three hot plates, two located in that portion of the top not overhung by the oven and one being arranged beneath the front end of the oven.

The switches 15 controlling the different 55 heat units are located in the front of the apron 12. The numeral 17 designates a broiler drawer which is slidably mounted in an opening in the front of the apron. In the double sided range shown in Fig. 1, a 60 switch panel is arranged at either side of the centrally located broiler drawer while in the single sided range shown in Fig. 2 the switches are all located to one side of the broiler drawer 17. 65

Carried by the back upright *b* at each side of the oven shown in Fig. 1, and at one side of the oven shown in Fig. 2, are shelves 18 which may be employed to support a water heater 19 or a cooking utensil, 70 like a percolator, chafing dish or flat iron. For purpose of illustration, a percolator is shown in full lines as located on the right hand shelf of the double sided range in Fig. 1. The heater 19 may have a separate heating element which is connected up with a plug or socket 21 located in the back upright and, if desired, another plug or socket 22 may be located in the back upright beneath the oven so that a portable cooking 80 utensil may be connected thereto, or, if desired, a light can be placed in this socket. In the double sided range, there is a third socket 24 to which the utensil located upon the right hand shelf 18 may be connected. 85

It will be seen from the foregoing description that, as the oven *c* is spaced above the top of the stove, there is a clear uninterrupted space across the top of the stove which insures a free circulation of air 90 across the top of the hot plates. This makes it agreeable for anyone to work at the range, as corners such as are present when the oven rests on the top of the stove and in which the heat becomes pock- 95 eted, are entirely eliminated. Furthermore, with the overhanging oven it is not necessary to make ranges constructed in accordance with the present invention left and right handed for it is immaterial whether the light comes from the right or the left as the space beneath the oven will allow proper illumination of that side of the top of the stove further away from the window through which the light comes. It will be 105 seen that the overhanging oven does not reduce the effective cooking area of the top 11, so that I obtain a greater cooking area 110

than can be had in other ranges of the same size. This means that the length or frontage of a range constructed in accordance with the present invention may be materially less than that of a range in which the oven rests on the top of the stove, and yet have an equivalent cooking area. By arranging the hot plates in the manner described, it is not necessary to reach over one hot plate to get to another hot plate.

The door 25 of the oven preferably swings about a vertical pivot through an angle of 180 degrees and has adjacent its lower edge an arc-shaped tray 26 which extends into the oven above the heating unit 27 when the door is closed. The tray 26 is slotted to allow the heat to pass to the utensil thereabove. This tray 26 is of advantage in that when it is desired to remove a pan from the oven, the door is opened through an angle of 90 degrees and the pan resting on the cleats or shelves in the oven is then drawn out and placed upon the arc-shaped tray whereafter the door can be swung into the full open position shown in Fig. 3 and in this position both handles of the pan may be readily grasped without any inconvenience or danger of burning the person handling the pan. In ovens having the usual let-down door, it is necessary to reach one hand into the front of the oven to grip the rear handle of the pan. Furthermore, the let-down door makes it inconvenient to get into the oven to clean the same, whereas with a swinging door having an arc-shaped tray, the door can be swung into full open position so that a person can get close to the oven and even where the door cannot be swung into full open position, a person can get nearer to the oven by stepping to the curved side of the arc-shaped tray.

It will be seen from Fig. 5 that the edges of the holes in the sheet metal top 11 and in which the hot plates 13 are located are flanged slightly as at 29 and the hot plate has a little angular groove adjacent its edge which fits over this flange.

In accordance with the present invention, I provide a broiler drawer 17 which is removably located in the range so that the drawer, together with the broiler *d* carried thereby, may be removed when it is desired to get at the broiler or to clean the drawer. In the present illustrative disclosure, there is located beneath the top of the stove a casing 30 forming a chamber which opens at its forward end into the apron 12 and into this casing the broiler drawer 17 is adapted to slide. It will be seen that the drawer 17 has a sliding fit in the casing 30, preferably the side and rear walls of the drawer being of substantially the same height as the casing and the front wall of the drawer being arranged to form a closure for the casing, which is of advantage in that grease or the

like cannot fly out of the drawer and the heat generated is retained within the casing. Suspended from the top of the casing 30 is an electrical heating element 31 and to permit the upper edge of the rear end of the drawer to clear this element, the rear wall of the drawer is cut away as at 33. In Figs. 5 and 6, I have illustrated the broiler as being supported by lugs 34 and 35 secured to the broiler drawer 17. It is preferable, however, to provide, as shown in Figs. 7 and 8, a pan 42 within the broiler drawer 17 and to support the broiler on the lugs 34 and 35 within this pan. The pan 42, which is somewhat shorter in length and narrower in width than the drawer 17, is positioned between the beveled cleats 43 riveted or otherwise secured to the bottom of the drawer. The broiler *d*, which is of novel construction, has a pair of hingedly connected sides or grids at the rear corners of each of which are laterally extending fingers 36 adapted to rest on the lugs 35 and the arrangement of the parts is such that the handles 50 of the grids are adapted to rest on the lugs 34. It will readily be seen from Fig. 6 that the broiler may be adjusted vertically relative to the heating element by moving the broiler from the lugs of one plane to those of another. It will also be seen that the broiler is always supported from its upper side or grid so that variations in the thickness of the meat being cooked are not material in adjusting the position of the meat relative to the heating element. When, as hereinafter described, the meat is properly clamped between the two grids of the broiler, after turning the broiler and then suspending the broiler from the same lugs as those from which it was previously suspended, the upper side of the meat is the same distance away from the heating plate or element 31 as was the other side of the meat when it was facing up. The rear end of the lugs 34 and 35 are bent upwardly to form stops which prevent the grids from moving rearwardly off of the lugs. In positioning the broiler on the lower lugs, it is clear that the fingers 36 are first positioned on the lower lugs 35, (this being easily accomplished as the lower lugs extend forwardly of the upper lugs) the broiler is then moved rearwardly of the drawer so that the handles of the grids will clear the upper lug 34, and then the broiler is moved forwardly to position the handle of the upper grid upon the lower lug 34. When the meat is to be turned, the drawer 17 is pulled out and then access can be readily had to the interior of the drawer to lift the broiler out, turn it over and replace it and all of this is done right in or over the drawer so that the drippings will go into the pan 42 or drawer 17 and cannot fall into the stove or on the floor during the cooking operation. The drawer or pan, of course, may

be properly enamelled or otherwise finished so it can be taken out of the stove and thoroughly cleaned.

- 5 The two sides or grids of the broiler are connected together at their rear ends by a pair of toggle links 37 so that the distance between the sides can be varied to accommodate meat or other articles of different thicknesses. The grids are clamped in position 10 against the meat by chains 38 and 39. The chain 38 is secured at one end to one grid and the other grid has a hook 40 to which the other end of the chain 38 may be adjustably secured. The other chain is permanently secured at one end to the handle of 15 one grid and is adapted to be passed about the handle of the other grid and then be adjustably secured to the handle of the first grid.
- 20 It is to be understood that the present disclosure of my invention is by way of illustration only and is not to be taken as restrictive thereof and that the invention is susceptible of various modifications and 25 changes which would be within the spirit of the invention without departing from the scope of the following claims.

What I claim is:—

1. In a range, a chamber, means for heating the same, and a broiler drawer removably located in said chamber beneath said heating means and having an imperforate bottom and also a front wall closing the front of said chamber.
- 30 2. In a range, a chamber having heating means in its upper portion, a broiler drawer removably located in and of substantially the same height and width as said chamber and having an imperforate bottom and also 35 a front wall forming a closure for said chamber.
- 35 3. In a range, a chamber, an electrical heating unit suspended from the top of said chamber, and a broiler drawer of substantially the same size as and removably located in said chamber, the rear wall of said drawer being cut away to clear said heating unit.
- 40 4. In a range, a chamber, means for heating the same, a broiler drawer removably

located in and of substantially the same height and width as said chamber and having an imperforate bottom and also a front wall forming a closure for said chamber, and means in said drawer for removably supporting a broiler.

5. In a range, heating means, a broiler comprising a pair of grids adapted to receive therebetween articles to be heated, and means for supporting said broiler from its upper 60 grid beneath said heating means.

6. In a range, an electrical heating unit, a removable drawer beneath said heating unit, a removable broiler comprising a pair of grids adapted to receive therebetween 65 articles to be heated, and cooperating means within said drawer and on said broiler for supporting the latter from its under side.

7. In a range, heating means, a removable drawer beneath said heating means, a pan in 70 said drawer, a removable broiler comprising a pair of grids adapted to receive therebetween articles to be heated, and cooperating means on said pan and broiler for supporting the latter from its upper side. 75

8. In a range, a removable drawer having a plurality of vertically spaced lugs and a removable broiler located in said drawer and comprising a pair of grids adapted to receive therebetween articles to 80 be heated, and means on each of said grids adapted to cooperate with said lugs.

9. In a range, a removable drawer having a lug at one end and a lug on each side adjacent its other end, and a broiler comprising two grids each provided with a handle adapted to engage said end lug and also provided at each forward end with a finger for cooperation with said side lugs.

10. In a range, a removable drawer having at its forward end and on each side adjacent its rear end sets of vertically spaced lugs, and a broiler having two grids each provided with a handle adapted to engage the lugs at the forward end of the drawer 95 and also provided at each forward corner with a finger for engaging with the lugs on the sides of the drawer.

JOSEPH F. LAMB.
